United States Patent Office

Des. 183,418
Patented Aug. 26, 1958

183,418

SUPPORT FOR PACKAGES OF DISPOSABLE PAPER AND THE LIKE

Ralph Covel, Pittsburgh, Pa.

Application March 27, 1956, Serial No. 40,799

Term of patent 14 years

(Cl. D52—2)

Fig. 1

Des. 183,418

PAGE 2

Fig. 3

Figure 1 is a perspective side view of a support for packages of disposable paper and the like, showing my new design;

The portions shown in dotted outline are for purpose of illustration only.

I claim:

The ornamental design for a support for packages of disposable paper and the like, substantially as shown and described.
